(57) **CLAIM**

The ornamental design for a medical handgrip, as shown and described.

DESCRIPTION

FIG. 1 is a perspective view of a medical handgrip showing our new design;

FIG. 2 is an enlarged left side elevational view thereof;

FIG. 3 is an enlarged right side elevational view thereof;

FIG. 4 is an enlarged top plan view thereof;

FIG. 5 is an enlarged bottom plan view thereof;

FIG. 6 is a rear elevational view thereof; and,

FIG. 7 is a front elevational view thereof.

The broken lines shown on the figures are included for the purpose of illustrating portions of the medical handgrip that form no part of the claimed design.
